UNITED STATES PATENT OFFICE

147,652

DESIGN FOR AN APRON

Harvey Ray Hill, Ogden, Utah

Application July 22, 1946, Serial No. 131,797

Term of patent 14 years

(Cl. D3—26)

To all whom it may concern:

Be it known that I, Harvey Ray Hill, a citizen of the United States, residing at Ogden, county of Weber, State of Utah, have invented a new, original, and ornamental Design for an Apron, of which the following is a specification, reference being had to the accompanying drawings, forming a part thereof.

In the drawings:

Fig. 1 is a front elevation of an apron showing my design.

Fig. 2 is a rear view thereof.

I claim:

The ornamental design for an apron, substantially as shown.

HARVEY RAY HILL.
